UNITED STATES PATENT OFFICE.

AUGUST STEGER, OF CHICAGO, ILLINOIS, ASSIGNOR OF ONE-FOURTH TO GEORGE A. WOODMAN, OF CHICAGO, ILLINOIS.

CAR-VENTILATOR.

1,389,788.

Specification of Letters Patent. Patented Sept. 6, 1921.

Application filed June 14, 1917. Serial No. 174,749.

To all whom it may concern:

Be it known that I, AUGUST STEGER, a citizen of the United States, residing at Chicago, in the county of Cook and State of

5 Illinois, have invented certain new and useful Improvements in Car-Ventilators, of which the following is a specification.

This invention relates to a ventilator for railway cars and has for its object the provision of means insuring an adequate flow 10 of air from the car under all conditions, preventing the entrance of cinders, snow and water through the ventilator opening and permitting the proper control of the flow 15 of air without diminishing the efficiency of the ventilator.

A further object of my invention is the provision of a screened ventilator from which the screen may be readily detached for repair or replacement without dismantling the 20 ventilator or removing it from the car.

Further objects and advantages of my invention will be apparent as it is better understood by reference to the following specification when read in connection with the accompanying drawing, illustrating the preferred embodiments thereof, in which—

Figure 1 is a plan view of the ventilator applied to the roof of a turtle-back car; 30 Fig. 2 is a section on the line 2—2 of Fig. 1;

Fig. 3 is a section on the line 3—3 of Fig. 2;

Fig. 4 is a section on the line 4—4 of 35 Fig. 2;

Fig. 5 is a detail in perspective of a double screen;

Fig. 6 is a detail in perspective of a single screen;

40 Fig. 7 is a transverse section through a slightly different form of ventilator adapted to be applied to the center of a turtle-back roof;

Fig. 8 is a plan view partially in section 45 of a ventilator constructed in accordance with my invention for use with a monitor deck car, and

Fig. 9 is a section on the line 9—9 of Fig. 8.

Referring to the drawing, 5 indicates 50 generally the roof of a turtle-back car having an opening 6 therein. Secured to the roof above the opening 6 is a shell preferably constructed of sheet metal and having top and bottom walls 7 and 8, respectively, a rear end wall 9 and a front wall 10. Side

walls 11 are supported between the top and bottom walls 7 and 8 and converge from the rear portion of the shell forming an air passage leading to an outlet.

A screen 12 is supported in the outlet, its 60 upper edge being disposed behind an angle member 13 secured to the top wall 7 and in front of angle members 14 secured to the lateral walls 11. Latches 15 are pivotally mounted on brackets 16 adjacent the bottom 65 wall 8 and when disposed in the position indicated in Fig. 1 retain the screen in operative position.

The screen may comprise a single sheet of screen cloth 17 bound as indicated in Fig. 70 6. Preferably, however, the screen comprises two sheets 18 of screen cloth spaced from each other by bending the edges of one sheet at right angles thereto and binding it with the edges of the other sheet as 75 indicated in Fig. 5. In either event the lower edge of the binding is provided with a plurality of notches 19, which when the screen is in operative position, are adjacent the bottom wall 8. The bottom wall 8 is 80 inclined downwardly toward the screen and consequently any cinders which may pass the screen will fall thereon and descend by gravity to the lower edge of the screen and thence through the notches 19 which permit 85 them to escape.

The inner end of the bottom wall 8 is provided with an upstanding flange 20 which effectively prevents either cinders, snow or water from passing into the opening in the 90 roof of the car. A door 21 is hingedly mounted at 22 on the rear wall 9 and cooperates with the flange 20 to close the air passage. A brace 22' connects the rear wall 9 with the flange 20 and a lever 23 is pivotally mounted at 24 thereon and is connected by a link 25 to a bracket 26 on the door 21. The pivotal point of the lever 23 is so related to the pivotal connection of the link 25 with the bracket 26 that when the door 100 21 is fully raised the pivotal connection of the link 25 with the lever 23 will have passed the line connecting the pivot 24 and the bracket 26 so that the door 21 is locked in open position.

A grid 27 is secured to the ceiling of the car over the opening leading to the air passage and is preferably of light but rigid construction. Heavy wire mesh fabric with a suitable binding at its edges is best adapted 110

for this purpose for the reason that it preserves the maximum capacity of the air passage. A slot 28 is provided in the grid 27 through which the end of the lever 23 projects. Thus the door 21 may be operated at will to open or close the air passage.

Between the top and bottom walls 7 and 8 adjacent to and at either side of the outlet I provide a plurality of baffles 29 which, together with the front wall 10, deflect any air currents from the outlet and thus prevent back pressure in the air passage. Upon examination it will be found that no direct line may be drawn from the point at which any air may enter between the top and bottom walls 7 and 8 which will extend into the outlet. This construction assures proper movement of the air through the air passage to the outlet under all conditions and also serves to decrease if not prevent the entrance of cinders, snow and water into the air passage.

In Fig. 7 I have illustrated the application of my invention to a double ventilator adapted to be applied to the center of a turtle-back roof. It will be understood that the shell 30 is constructed exactly in accordance with the principles just described. The doors 31 are controlled by levers 32 projecting through the opening 33 in the car roof and through suitable slots in the grid 34. The screens 35 occupy the same relative position as in the structure heretofore described as do also the baffles 36. The structure shown in Fig. 7 is in fact two ventilators placed back to back.

In Figs. 8 and 9 of the drawing I have illustrated a form of my invention adapted for use in "monitor-deck" cars. Referring to the drawing, 35 indicates the roof of the car in the central portion of which the monitor 36 is arranged. A transom 37 is provided to permit the escape of air from the car. My invention as applied to this type of car is substantially identical in every respect with the form hereinbefore described except that the transom 37 serves the purpose of the door 21 and the shell 38 is slightly modified so that it may be fastened to the monitor 36 as indicated in the drawing. A screen 39 is provided and held in operative position by latches 40 so that it may be readily removed for repair or replacement. The bottom wall 41 of the air passage slopes downwardly toward the outlet in which the screen 39 is disposed so that cinders which pass the screen may escape. Baffles 42 are provided at either side of and in front of the outlet to deflect air currents therefrom.

From the foregoing it will be readily understood that I have perfected a ventilator

for cars presenting numerous advantageous features and capable of accomplishing results which are impossible with the types of ventilators now in use. It will be apparent, moreover, that various changes may be made in the form, construction and arrangement of the parts without departing from the spirit and scope of the invention or sacrificing any of the material advantages thereof, the forms hereinbefore described being merely preferred embodiments thereof.

I claim:

1. A car ventilator comprising a shell having top and bottom walls, side walls converging from the outer edges of said top and bottom walls to provide a centrally disposed outlet, a screen across said outlet, baffles located at the sides of said outlet, and baffles located in front of said first mentioned baffles and projecting angularly in front of said outlet.

2. A car ventilator comprising a shell having a top, front and back walls, a bottom wall having an opening therein, side walls converging from the outer edges of the top and bottom walls and inclosing the front portion of said opening to form a central outlet located back of the front wall, a baffle at each side of said opening, and baffles located between the front and said first mentioned baffles and projecting from the outer edges of the top and bottom walls to a position in front of said outlet.

3. A car ventilator comprising a shell having top and bottom walls, side walls converging from the outer edges of said top and bottom walls to provide an outlet, and a screen secured in said outlet, said bottom wall being inclined at said outlet and said screen having openings in its lower edge to permit the escape of cinders which may pass through the screen and fall upon said bottom.

4. A car ventilator comprising a shell having top, front and back walls, a bottom wall having an opening therein, converging side walls forming an outlet, and a double screen supported in said outlet.

5. A car ventilator comprising a shell having top, front and back walls, a bottom wall having an opening therein, converging side walls inclosing the front portion of said opening and forming an outlet, an inclined door hinged to the shell at the top thereof behind the outlet to close the passage leading thereto, means for operating said door, and a screen in said outlet in front of said door.

AUGUST STEGER.
